REFRIGERATING APPARATUS

James R. Stephenson, Dayton, Ohio, assignor,
by mesne assignments, to General Motors Corporation, a corporation of Delaware

Application April 26, 1933, Serial No. 667,991
Renewed December 3, 1936

11 Claims. (Cl. 230—232)

This invention relates to refrigeration and more particularly to a refrigerating system in which the motor and compressor are assembled as a unit within a resonant casing.

An object of this invention is to provide proper heat dissipating means for the motor-compressor unit of the system in the form of fins, but in such a manner that undue noises heretofore produced in units of this kind are obviated.

Further objects and advantages of the present invention will be apparent from the following description, reference being had to the accompanying drawing, wherein a preferred form of the present invention is clearly shown.

In the drawing:

Fig. 1 is a view partly in perspective, partly in cross-section, and diagrammatic of a system embodying features of my invention; and

Fig. 2 is a horizontal cross-section taken transversely of a pair of fins.

A refrigerating system embodying features of my invention comprises in general a motor-compressor unit 10, which delivers compressed refrigerant to a condenser 11, where the refrigerant is liquefied and from whence it passes through the line 12 to an evaporator 13 through an expansion device 14, in which evaporator the refrigerant is evaporated and returns through the line 15 to the unit 10.

The motor-compressor unit 10 may include a compressor 16 and a motor 17 within a hermetic sheet metal casing 18. The motor and compressor may be of any desired form. Thus the compressor 16 may be of the rotary type, and the motor 17 may include a stator 19 supported directly on casing 18 and a rotor 20 rotatably disposed within the casing.

The casing 10 may be provided with fins 21 and 21' which are radially disposed along the cylindrical casing 18 and are secured thereto in any desired manner. Thus each pair of fins 21 and 21' may be joined by an internal flange 22 which may be spot-welded to the casing 18. The outer extremities of each of the fins 21 may be in the form of a flange 23 which is directed towards a similarly disposed flange 23' of the adjacent fin 21' which thus form a series of pairs of fins with flanges directed towards each other circumferentially arranged around the casing 18.

The fins are provided with vibration damping means to prevent the noise producing vibrations which exist in these fins, the action of which has hitherto been undiscovered. The vibration

damping means may be in the form of wooden strips 24 bridging the extremities of the fins. A convenient form of strip is one having notches 25 at opposite sides through which the ends of the flanges 23 and 23' may pass while the strips 24 are being driven longitudinally between the flanges. Thus, the fins 21, 21' together with the strips 24 form non-resonant heat radiating means for the compressor.

In operation the heat of the motor-compressor unit is dissipated through the fins 21 and 21' by air passing upwardly along and between the fins. The action of the motor and compressor is such that vibrations, in units not embodying my invention, are created on these fins, particularly if such fins are made of sheet metal in order to reduce their cost. These vibrations, I find are very effectively damped by the use of the wooden strips as heretofore described and thus the quietness of the unit is very materially enhanced.

While the form of embodiment of the invention as herein disclosed, constitutes a preferred form it is to be understood that other forms might be adopted, all coming within the scope of the claims which follow.

What is claimed is as follows:

1. A motor-compressor unit for refrigerating systems and the like having a motor, a compressor, a hermetically sealed casing around said motor and compressor, radially directed fins on said casing, said fins having flanges directed towards each other at their outer extremity, and vibration damping means for said fins bridging said flanges.

2. A motor-compressor unit having a motor, a compressor, a cylindrical hermetically sealed casing around said motor and compressor, radially directed fins parallel to the axis of said casing disposed about the periphery of said casing, and wooden members bridging the outer extremities of said fins.

3. A motor-compressor unit having a motor, a compressor, a cylindrical hermetically sealed casing around said motor and compressor, radially directed fins parallel to the axis of said casing disposed about the periphery of said casing, said fins having tangentially disposed flanges forming the outer extremities of said fins, and wooden members bridging the outer extremities of said fins.

4. A motor-compressor unit for refrigerating systems and the like having a motor, a compressor, a hermetically sealed casing around said motor and compressor, radially directed fins on

said casing, said fins having flanges directed towards each other at their outer extremity, and vibration damping means for said fins bridging said flanges and maintaining said fins under permanent stress.

5. A motor-compressor unit for refrigerating systems and the like having a motor, a compressor, a hermetically sealed casing around said motor and compressor, radially directed fins on said casing, said fins having flanges directed towards each other at their outer extremity, and vibration damping means for said fins formed of non-resonant material bridging said flanges.

6. A motor-compressor unit for refrigerating systems and the like having a motor, a compressor, a hermetically sealed casing around said motor and compressor, radially directed fins on said casing, said fins having flanges directed towards each other at their outer extremity, and vibration damping means for said fins formed of non-resonant material bridging said flanges and maintaining said fins under permanent stress.

7. A motor-compressor unit having a motor, a compressor, a cylindrical hermetically sealed casing around said motor and compressor, radially directed fins parallel to the axis of said casing disposed about the periphery of said casing, said fins having tangentially disposed flanges forming the outer extremities of said fins, and members bridging the outer extremities of said fins, said members comprising non-resonant material.

8. A motor-compressor unit having a motor, a compressor, a cylindrical hermetically sealed casing around said motor and compressor, radially directed fins parallel to the axis of said casing disposed about the periphery of said casing, said fins having tangentially disposed flanges forming the outer extremities of said fins, and members bridging the outer extremities of said fins, said members comprising material having a resonance different from the material of said fins.

9. A motor-compressor unit having a motor, a compressor, a cylindrical hermetically sealed casing around said motor and compressor, radially directed fins parallel to the axis of said casing disposed about the periphery of said casing, and non-metallic members bridging the outward extremities of said fins.

10. A motor-compressor unit having a motor, a compressor, a cylindrical hermetically sealed casing around said motor and compressor, radially directed fins parallel to the axis of said casing disposed about the periphery of said casing, said fins having tangentially disposed flanges forming the outer extremities of said fins, and non-metallic members bridging the outer extremities of said fins.

11. A motor-compressor unit having a motor, a compressor, casing means for said motor and compressor, heat radiating fins on said casing, and non-resonant members bridging the outer extremities of said fins.

JAMES R. STEPHENSON.
